UNITED STATES PATENT OFFICE

118,692

DESIGN FOR A SHOE

Thomas F. Carfagno, Hanover, Pa., assignor to Cannon Shoe Company, Baltimore, Md., a corporation of Massachusetts

Application March 1, 1939, Serial No. 83,273

Term of patent 3½ years

To all whom it may concern:

Be it known that I, Thomas F. Carfagno, a citizen of the United States, residing at the Borough of Hanover, York County, State of Pennsylvania, have invented a new, original, and ornamental Design for Shoes, of which the following is a specification, reference being had to the accompanying drawing, forming a part thereof.

The design of my shoe is characterized by the staggered arrangement of straps woven through slots provided for in the top part of the shoe, said straps are woven from one side of the shoe and extend rearwardly to the center portion thereof then extend forwardly on the other side of the shoe.

I claim:

The ornamental design for a shoe, as shown and described.

THOMAS F. CARFAGNO.
